UNITED STATES PATENT OFFICE.

JOHN A. ARVIDSON, OF SAN FRANCISCO, CALIFORNIA.

APPARATUS FOR SHOWING COMPASS DEVIATION.

SPECIFICATION forming part of Letters Patent No. 538,889, dated May 7, 1895.

Application filed November 23, 1894. Serial No. 520,766. (No model.)

To all whom it may concern:

Be it known that I, JOHN A. ARVIDSON, a citizen of the United States, residing in the city and county of San Francisco, State of California, have invented an Improvement in Apparatus for Showing Compass Deviation; and I hereby declare the following to be a full, clear, and exact description of the same.

My invention relates to an apparatus which is designed to show the deviation of magnetic compasses, and is especially applicable for the adjustment of such deviation, so that the courses sailed by the ship can be accurately determined at all times, when heavenly bodies are visible.

It consists in certain details of construction which will be more fully explained by reference to the accompanying drawings, in which—

20 Figure 1 is a view of my apparatus. Fig. 2 is a view of the additional segment to the compass-card. Fig. 3 is a detail view of the observing tube.

A is a circular compass card supported upon 25 gimbals in the usual way, and having a counterbalance weight by which it is retained in an essentially horizontal position independent of the movements of the vessel, unless the latter be very violent. To the same support are 30 fixed the standards B, and in these standards a circular ring C is journaled by means of pivot pins D projecting from opposite sides. This ring has marked upon it scales showing the apparent time, during the whole twenty-four hours of the day, and within it is fitted 35 a disk E which is adapted to rotate within the ring. This disk is slotted across the center and has an observing tube F pivoted in the center as shown at G so as to be capable 40 of movement about its pivot pins to be raised or depressed with relation to the plane of the disk. In exact line with the center of this observing tube are points or indicators H which project so as to coincide with any one 45 of the time marks shown on the inner periphery of the circle. This observing tube has cross lines or wires, as shown at I, at one end, and the other end has an open slot made in it as shown at J. The end or bottom which 50 is observable through this slot has cross lines K made upon it coinciding with the cross wires I at the opposite open end of the tube, so

that when the tube is set in the proper direction, the light of the sun falling through it, will cause the shadow of the cross lines I to fall upon those shown at K and coincide with them. The time ring C has fixed to it a semi-circular arc M. This semi-circular arc is fixed to the time ring so as to extend below it and at right angles with the pivot pins D. Upon the 55 inner periphery of this arc is marked a scale of degrees which indicates the declination, and upon its outer periphery a scale of degrees indicating latitude. At a central point beneath this segment are a clamp N by which 60 it may be locked at any desired position, and a stationary index or point, which shows upon the exterior scale the number of degrees at 65 which it may be set.

The operation of the apparatus will then be 70 as follows: When it is desired to take an observation for the purpose of ascertaining the deviation of the compass, the latitude and the declination at that point being known, the inner disk carrying the telescope or observa- 75 tion tube is first turned so that the tube is in line with the latitude and declination segment. By means of an index pointer O upon the end of the tube, the declination at that particular point being known, the tube is 80 turned upon its pivots until the index coincides with the marking for that declination. The outer circle C is then turned about its pivot points upon the standards until the degree indicating the latitude of that particu- 85 lar point coincides with the index pointer below the circle when the clamping screw is turned and the semi-circle is locked at that point. The inner disk is now turned around within the circle C until the index pointer, in 90 line with the observation tube, stands opposite the figure indicating the time at that instant, and the apparatus is then turned or set so that the sun shining into the open end of the tube will throw the shadow of the cross 95 hairs or wires at that end of the tube upon the corresponding cross made on the inner opposite end of the tube which can be seen through the opening J which is made at that point. When these cross wires or lines intersect, the points Q of the compass familiarly called the lubber points, will show the true meridional heading of the ship. The true va- 100 riation is shown upon tables prepared for the

purpose and upon charts, and having this, the rubber points are adjusted to the variation, and the difference between the heading shown by the standard compass, and that 5 shown by the compass of this apparatus, will be the deviation, as shown in Fig. 2. The difference between this and the standard compass will be the deviation on that course as long as that course is continued. Whenever 10 a new course is taken the adjustment may be made again for time, the latitude and declination being approximately the same for several observations, and the observation and correction made for the new course.

15 If a master leaving port upon a new vessel, or one in which the deviation of the compass is not known, desires to ascertain this deviation, it may be done with this instrument by putting the vessel successively upon 20 various courses around the entire circle, and noting the deviation for each course. By making an observation hole through the center of the end having the cross lines K, a direct observation may be made upon a star or 25 other heavenly body not large enough to make a shadow of the cross wires, and the necessary data can thus be obtained.

This instrument may also be used to obtain 30 the true bearing of distant points, by fixing sights R upon the observation tube, and the bearing can be noted by the scale of degrees upon the outer periphery of the ring C when the latter has been turned to bring the tube in the proper line.

35 Having thus described my invention, what I claim as new, and desire to secure by Letters Patent, is—

1. An apparatus for showing deviation of compasses consisting of a time circle journaled 40 in standards which are supported and turnable in conjunction with a compass, suspending mechanism whereby the compass card is maintained in an essentially horizontal position, a latitude and declination circle fixed to 45 the lower side of the ring at right angles with its journals with an index and clamp for adjusting and holding it, a disk rotatable within the time ring having an opening made transversely across it, an observation tube journaled 50 in the opening in the rotatable disk so as to turn transversely thereto, and an index point in the plane of movement of the observation tube adapted to coincide with the apparent time when the observation is taken.

55 2. An apparatus to show the deviation of compasses consisting of a compass card suspended and counterbalanced so as to maintain an approximately horizontal position, standards supported therefrom, an annular 60 ring having marked upon its periphery the times from noon to midnight, and midnight to noon, a disk having a corresponding axis

and rotatable within the ring, an observation tube pivoted in a channel made transversely across the disk and turnable about its pivots 65 with relation to the plane of the disk, cross wires fixed in the open end of the tube and a corresponding cross marked upon the inner side of the opposite closed end, with openings through which it may be seen, an index fixed 70 to the disk adapted to coincide with the time of observation as marked upon the time ring, a semi-circular arc fixed to the lower side of the time ring and at right angles with its axis of rotation, having the degrees of latitude 75 marked upon its outer periphery, and a fixed index and clamp centrally beneath it whereby it may be adjusted and held, and degrees of declination marked upon its inner periphery, an index pointer fixed to the observation tube 80 adapted to be adjusted with relation to the declination circle for the latitude in which the observation is taken.

3. An apparatus for showing the deviation of compasses at sea, consisting of a tube open 85 at one end which is presented toward the sun or other solar object, and having crossed wires therein, a table upon the inner side of the opposite closed end having a corresponding cross marked thereon with which the 90 shadow of the wires will coincide when the tube is properly set for the observation, and openings upon each side of this end of the tube through which the coincidence of the cross lines may be observed, a disk rotatable 95 within a ring, which ring has marked upon it the apparent times for the twenty-four hours, and an index pointer by which the disk may be set to correspond with the time when the observation is to be taken, journal-pins in a slotted 100 opening extending from side to side of the disk, upon which journal pins the tube is turnable within the slot, a declination ring having degrees marked upon its inner periphery, and an index pointer upon the tube 105 adapted to coincide with the markings of the declination ring whereby the tube may be set to the known declination in a given latitude, and degrees upon the outer periphery of the semi-circle adapted to coincide with a central 110 point fixed below the center of the apparatus, and a clamp by which it is held when the adjustment has been made, in combination with a compass card upon which the apparatus is supported, said card being maintained in an 115 approximately horizontal position by gimbals and a counterbalance weight.

In witness whereof I have hereunto set my hand.

JOHN A. ARVIDSON.
